UNITED STATES PATENT OFFICE.

WILLIAM NORTON, OF SAN FRANCISCO, CALIFORNIA.

ANTISKIDDING DEVICE FOR MOTOR-VEHICLES.

1,147,040.

Specification of Letters Patent. Patented July 20, 1915.

Application filed March 20, 1915. Serial No. 15,915.

To all whom it may concern:

Be it known that I, WILLIAM NORTON, a citizen of the United States, residing at San Francisco, in the county of San Francisco and State of California, have invented certain new and useful Improvements in Anti-skidding Devices for Motor-Vehicles, of which the following is a specification, reference being had to the accompanying drawing.

This invention relates to an improved anti-skidding device for motor vehicles, and has for its primary object to provide a very simple and effective device for this purpose, whereby sidewise skidding or sliding movement of the vehicle upon treacherous road surfaces may be prevented.

The invention has for an additional object to provide an anti-skidding device for vehicles embodying a vertically movable part mounted upon the vehicle frame and provided on its lower end with a road engaging shoe, and manually operable means for lowering or raising said part to dispose the shoe in effective engagement with the road surface or in an elevated inoperative position.

It is a further general object of the invention to produce a device of the above character which is strong and durable in its construction, inexpensive to manufacture and readily applicable to the vehicle without necessitating any changes in its construction, and is highly convenient and serviceable for the purposes in view.

With the above and other objects in view, my invention consists in the novel features of construction, combination, and arrangement of parts to be hereinafter more fully described, claimed, and illustrated in the accompanying drawing, in which,

Figure 1 is a side elevation showing the present invention applied to a motor vehicle frame, the shoe being illustrated in its lowered position in dotted lines; Fig. 2 is a top plan view; Fig. 3 is a section taken on the line 3—3 of Fig. 1; and Fig. 4 is a detail perspective view of the shoe.

In the accompanying drawing, I have shown my invention applied to a motor vehicle frame or chassis 5 which is mounted in any ordinary or approved manner upon the usual front and rear axles 6 and 7, respectively, upon the ends of which the supporting wheels 8 are arranged. The frame structure 5 includes spaced intermediate

transverse bars 9 and the rear parallel longitudinal bars 10.

The invention forming the subject matter of the present application, includes a vertically disposed metal guide sleeve or tube 11 which extends between and above and below the longitudinal frame bars 10. Intermediate of its ends, this sleeve is provided with oppositely extending lugs or ears 12 to be disposed upon the under sides of the longitudinal bars 10 and secured thereto by suitable bolts indicated at 13. The lower end of the tube 11 is provided with similar ears 14 to which the lower ends of the inclined truss bars 15 are bolted, the other ends of said bars being secured in the frame bars 10. Within the sleeve or tube 11, a vertically movable rod 16 is loosely engaged, the lower end of said rod being enlarged and bifurcated to receive the longitudinally disposed shoe 18. This shoe is constructed with a central steel core bar indicated at 19, upon each side of which an iron bar 20 is arranged and welded to the steel bar. This steel core 20 of the shoe is of extreme hardness so that the relatively soft side portions of iron will wear away and leave the central steel bar in such form as to securely grip the road surface. The shoe is thus, in effect, self-sharpening.

Upon one of the transverse bars 9 of the vehicle frame, a hanger bearing or support 21 is secured by the bolts 22. This hanger includes a downwardly extended bifurcated arm 23 and the spaced upwardly extending ears 24 which are formed upon the upper end of the hanger and are disposed out of vertical alignment with the arm 23. The lower end of the arm 23 is bifurcated to receive one end of a rod 25 which is provided with a longitudinal slot 26 in which a pin 27, fixed in the bifurcated end of the arm 23, is engaged. The other end of the rod 25 is pivotally connected, as at 28, to the forward end of the shoe 18. In the upwardly projecting ears 24 of the hanger, a lever 29 is fulcrumed adjacent to its lower end. In a bracket member 30 fixed to the rear transverse bar 9 of the vehicle frame, a bell crank lever 31 is fulcrumed and the outwardly projecting arm 32 of this lever is pivotally connected to the rear end of a bar 33, the forward end of which is pivoted to the lower end of the lever 29. The other arm of the bell crank lever 34 extends rearwardly, and to the same the upper end of a rod 35 is

pivots connected. The lower end of this rod is pivotally connected, as at 36, to the lower end of the vertically movable rod 16.

From the foregoing description, the operation of my invention will be understood as follows. Assuming that the parts are in the position shown in dotted lines in Fig. 1, when icy or slippery road surfaces are encountered, the operator shifts the lever to 10 the dotted-line position, and thus actuates the bell crank 31 to force the rod 35 downwardly and thus also slide the rod 16 downwardly in the sleeve 11 and lower the shoe 18 into contact with the road surface. The 15 shoe is effectually braced to withstand longitudinally applied pressures by means of the rod 25 which is connected to the forward end of the shoe. In this manner, it will be seen that the anti-skidding shoe may be very 20 easily and quickly lowered into engagement with the road surface or elevated by a reverse movement of the lever to the inoperative position shown in full lines in Fig. 1. It will, of course, be obvious that, if desired, 25 a foot pedal may be substituted for the hand lever 29. The mechanism for operating the shoe might also be actuated by compressed air controlled through the medium of a suitable valve by the operator.

30 The several parts of the device are all of very simple form and may be easily and quickly assembled and applied to any of the various makes of motor vehicles at nominal cost. The invention is also positive in its 35 action, as well as highly efficient and reliable in practical use.

While I have shown and described the

preferred construction and arrangement of the several elements employed, it is obvious that the device is susceptible of considerable 40 modification therein, and I, therefore, reserve the privilege of resorting to all such legitimate changes as may be fairly embodied within the spirit and scope of the invention as claimed.

Having thus fully described my invention, what I desire to claim and secure by Letters Patent is:—

The combination with a motor vehicle including a frame, of a vertically disposed guide sleeve fixed in said frame, a rod vertically slidable in said sleeve, a longitudinally extending shoe secured to the lower end of said rod, a hanger bracket fixed upon the machine frame and having a downwardly extending arm, a rod pivotally connected to one end of the shoe at its rear end and slidably connected to the bracket arm at its other end, an operating lever mounted upon said bracket, a bell crank lever fulcrumed in the frame, a rod connected to one arm of said lever and to the lower end of the vertically slidable rod, and a connecting rod between the other arm of said bell crank and the lower end of the operating lever whereby said shoe may be lowered or raised to its operative or inoperative position.

In testimony whereof I hereunto affix my signature in the presence of two witnesses.

WILLIAM NORTON.
